UNITED STATES PATENT OFFICE.

PHILLIP HIEN, OF CHICAGO, ILLINOIS.

SLACK-ADJUSTER.

SPECIFICATION forming part of Letters Patent No. 777,098, dated December 13, 1904.

Application filed February 20, 1903. Serial No. 144,193. (No model.)

To all whom it may concern:

Be it known that I, PHILLIP HIEN, a citizen of the United States, residing at Chicago, county of Cook, State of Illinois, have invented 5 a certain new and useful Improvement in Slack-Adjusters; and I declare the following to be a full, clear, and exact description of the invention, such as will enable others skilled in the art to which it pertains to make and use the same, reference being had to the accompanying drawings, which form a part of this specification.

My invention relates generally to railway-brakes, and more particularly to slack-adjusters.

In order that the brakes of a car may be applied with maximum efficiency, it is necessary that the slack in the brake-rigging, which constantly results from the wearing away of the 20 brake-shoes, should be eliminated as fast as it occurs, and thereby prevent an increase in the throw of the piston and the consequent decrease in pressure per square inch in the brake-cylinder. In slack-adjusters as usually constructed the slack is only removed when a 25 predetermined amount exists. Consequently the maximum braking pressure is only available immediately after the operation of the adjuster, and during the existence of less slack 30 than the predetermined amount the brakes are operated at less than maximum efficiency.

The primary object of my invention is to provide a slack-adjuster which will take up any existing slack each time the brakes are applied, thereby maintaining the throw of the 35 brake-piston constant and securing the greatest braking efficiency at each application of the brakes.

A further object of my invention is to provide a slack-adjuster which will be simple in construction, inexpensive in manufacture, and efficient in operation.

My invention will be more fully described hereinafter with reference to the accompanying 45 drawings, in which the same is illustrated as embodied in a convenient and practical form, and in which—

Figure 1 is a perspective view of a brake-cylinder and a portion of the brake-rigging 50 with my improved adjuster applied thereto;

Fig. 2, an elevational view of a portion of my adjuster; Fig. 3, an elevational view of the casing, forming part of my adjuster; Fig. 4, a horizontal sectional view of the complete adjuster and co-operating parts of the brake-rigging, and Fig. 5 a sectional view on line 55 5, Fig. 4.

Similar reference characters are used to indicate similar parts in the several figures of the drawings.

Reference-letter A designates a brake-cylinder in which the piston is adapted to reciprocate.

a indicates the piston-rod, to which is pivotally connected the brake-lever *B'*.

b' indicates the connecting-rod, which extends from the lever *B'* to the live and dead levers at one of the trucks of the car.

*B*² indicates the second brake-lever, which is pivoted between the lugs *a'*, projecting from 70 the cylinder-head.

*b*² designates the connecting-rod, which extends to the live and dead levers at the other truck under the car.

The brake-cylinder and brake-rigging above 75 described are in common use and form no part of my invention.

It is customary to connect the levers *B'* and *B*² at points intermediate of their ends by a shaft which communicates movement to the lever *B*² from the lever *B'*. In lieu of the usual shaft connecting the levers *B'* and *B*², I provide a shaft *C*, the ends of which are oppositely screw-threaded and which engage screw-threaded openings formed in the 85 buckles *c'* and *c*². These buckles are preferably formed integrally with the castings *C'* and *C*², which are bifurcated and surround the levers *B'* and *B*², respectively; to which they are pivotally connected.

Surrounding and fixed to the shaft *C* is a ratchet-wheel *D*. Any suitable means may be employed for non-rotatably fixing the ratchet-wheel upon the shaft *C*—such, for instance, as pins *d*, extending through the hubs of the 95 ratchet-wheel and through the shaft. Loosely mounted upon the shaft *C* is a casing *E*, which surrounds the ratchet-wheel *D*. A cover *E'* surrounds the shaft *C* on the opposite side of the ratchet-wheel from the casing *E* and is 100

secured to the casing E by any suitable means—such, for instance, as screws e' .

Pivotedly supported within the casing E is a pawl F, adapted to engage the teeth of the 5 ratchet-wheel D. The pawl may be conveniently supported in the casing by means of trunnions f, which extend through registering openings formed in the casing E and cover E'. A headed pin F' projects upwardly from 10 the pawl and extends through the casing E, thereby affording means for disengaging the pawl from the ratchet-wheel.

Projecting laterally from the casing E is a spirally-disposed incline E³, which may be recessed, as shown at e^3 , to afford a space for a 15 lubricant. A second spirally-disposed incline E⁴ is preferably provided at the point on the casing E' diametrically opposite the first incline E³.

20 A bracket G loosely surrounds the shaft C and is fixed against movement by any suitable means—such, for instance, as a horizontal flange G'—through holes in which bolts are passed into engagement with the bottom of the car or other support. The bracket G may be conveniently so proportioned that its fastening-flange G' occupies the same horizontal plane as the flange A' on the brake-cylinder. The bracket G supports spirally-dis- 25 posed inclined planes G³ and G⁴, which conform in curvature to the inclines E³ and E⁴ and which are located the same distances from the shaft C as are the inclines E³ and E⁴. The bracket G is provided with a lateral extension 30 in which is formed a slot G². A guide-finger E² is fixed upon the casing E and extends through the slot G².

A handle H is fixed upon the shaft C and is preferably provided with a collar h, located 40 adjacent to the hub of the casing E and which serves as a stop to assume the strain which may be imposed upon the casing during the operation of the adjuster.

The operation of my invention is as follows: 45 When the brakes are applied, compressed air flows into the brake-cylinder and so moves the piston therein that the lever B' is oscillated about the casting C'. Power is transmitted from the lever B through the casting C', shaft 50 C, and casting C² to the lever B² and oscillates the latter about its pivotal connection with the lugs a'. The position of the bracket G is such that the movement of the shaft C carries the casing E to such a position that the inclines E³ and E⁴ thereon engage the inclines G³ and G⁴. When there is no slack 55 in the brake-rigging, the brake-shoes are applied to the wheels of the car when the inclines E³ and E⁴ engage the inclines G³ and G⁴; but 60 when any slack exists the movement of the shaft C is more extended, and hence the inclines E³ and E⁴ are moved through engagement with the inclines G³ and G⁴, thereby correspondingly rotating the casing E, and 65 through the engagement of the pawl F, car-

ried by the casing with a tooth on the ratchet-wheel D, the shaft C is rotated, thereby turning the screw-threaded ends thereon within the screw-threaded openings in the buckles c' and c². The distance between the buckles 70 c' and c² is consequently decreased and the levers B' and B² drawn closer together, thereby eliminating the slack. When the air is exhausted from the brake-cylinder and the levers B' and B² resume their normal positions, 75 the casing E is carried away from the bracket G and the inclines E³ and E⁴ disengaged from the inclines G³ and G⁴. As soon as the inclines permit, the casing rotates by gravity in a reverse direction from that in which it is 80 moved by the engaged inclines, such movement of the casing by gravity being limited by the finger E² engaging the bottom of the slot G². As the casing only falls back by gravity the distance which it was rotated by 85 the inclines, it is evident that the pawl F will be moved with respect to the ratchet-wheel merely the corresponding distance, and only when the movement by the engaged inclines has rotated the ratchet-wheel a distance cor- 90 responding to one tooth thereon will the pawl fall into engagement with the succeeding tooth upon the release of the brakes.

When the new brake-shoes are substituted 95 for those which have been worn out, it is necessary to let out the slack which has been taken up—that is, lengthen the shaft between the levers B' and B², so that the new brake-shoes will not be forced against the wheels with such power as to lock the wheels against 100 rotation. This may be readily done by lifting the pawl out of engagement with the teeth on the ratchet-wheel and then rotating the shaft C in a reverse direction by means of the handle H.

105 From the foregoing description it would be observed that I have invented an improved slack-adjuster which will remove any existing slack each time the brakes are applied and which permits the slack to be readily let out 110 when new shoes are secured to the brake-beams in lieu of those which have been worn out.

While I have described more or less precisely the details of construction, I do not wish 115 to be understood as limiting myself thereto, as I contemplate changes in form, the proportion of parts, and the substitution of equivalents as circumstances may suggest or render expedient without departing from the spirit 120 of my invention.

Having now fully described my invention, what I claim as new, and desire to secure by Letters Patent, is—

125 1. In a slack-adjuster, the combination with the brake-rigging comprising a rotatable shaft having a screw-threaded connection with a non-rotating co-operating part, of a support rotatively mounted upon said shaft, a pawl-and-ratchet connection interposed between 130

said shaft and said support, means for rotating said support in a direction to impart rotary movement to said shaft through the pawl-and-ratchet connection during the application

5 of the brakes.

2. In a slack-adjuster the combination with a rotary shaft, of a non-rotative part in screw-threaded engagement with said shaft, a casing rotatively mounted on said shaft, a pawl 10 pivotally supported in said casing, a ratchet-wheel fixed upon said shaft and surrounded by said casing, and means for rotating said casing in a direction to impart rotary movement to said shaft through the engagement of 15 said pawl with said ratchet during the application of the brakes.

3. In a slack-adjuster, the combination with the brake-rigging comprising a rotatable shaft having a screw-threaded connection with a co- 20 operating non-rotatable part, of a ratchet-wheel fixed upon said shaft, a casing surrounding said ratchet-wheel and rotatively supported upon said shaft, a pawl mounted upon said casing, a spirally-disposed incline 25 carried by said casing, a coöperating fixed incline located in the path of movement of the incline on the casing when the brakes are applied whereby said shaft is rotated through the engagement of the incline on the casing 30 with the fixed incline.

4. In a slack-adjuster, the combination with a rotatable shaft, of a non-rotatable coöperating part in screw-threaded engagement with said shaft, a ratchet-wheel fixed upon said 35 shaft, a casing surrounding the ratchet-wheel and rotatively supported by the shaft, a pawl coöperating with said ratchet-wheel and pivotally supported by said casing, means for rotating said casing when the brakes are applied 40 in a direction to cause said pawl and ratchet to effect a rotation of said shaft, said casing adapted to move by gravity in a direction to disengage said pawl from the teeth on said ratchet-wheel.

5. In a slack-adjuster, the combination with a rotatable shaft, of a non-rotatable part in screw-threaded engagement with said shaft, a fixed guide through which said shaft passes, a spirally-disposed incline on said guide, a 45 casing surrounding said shaft and loosely supported thereby, a ratchet-wheel fixed upon said shaft, a pawl carried by said casing and adapted to engage said ratchet-wheel, a spirally-disposed incline carried by said casing 50 adapted when the brakes are applied to en-

gage the incline on said guide to rotate said casing and thereby through the engagement between said pawl and ratchet-wheel rotate said shaft.

6. In a slack-adjuster, the combination with a rotatable shaft, of a coöperating non-rotatable part having screw-threaded connection with said shaft, a ratchet-wheel fixed upon said shaft, a casing surrounding the ratchet-wheel and rotatively supported by said shaft, 60 a pawl pivotally mounted within said casing, means for rotating said casing during the application of the brakes in a direction to rotate said shaft through said pawl and ratchet, 65 said casing adapted to rotate in a reverse direction by gravity upon the release of a brake, and means for limiting the movement of said casing by gravity.

7. In a slack-adjuster, the combination with a rotatable shaft, of a coöperating non-rotatable 70 part having screw-threaded connection with said shaft, a ratchet-wheel fixed upon said shaft, a casing surrounding the ratchet-wheel and rotatably supported by said shaft, a pawl carried by said casing, a spirally-disposed 75 incline projecting laterally from said casing, a fixed guide through which said shaft passes, a spirally-disposed incline upon said guide located in the path of movement of the incline of the casing when the brakes are applied, 80 a finger fixed to said casing and projecting through a slot in said guide for limiting the rotary movement of said casing.

8. In a slack-adjuster, the combination with a rotatable shaft, of a non-rotatable coöperating 85 part in screw-threaded engagement with said shaft, a ratchet-wheel fixed upon said shaft, a casing surrounding the ratchet-wheel and rotatably supported by the shaft, a pawl carried by said casing, a spirally-disposed incline 90 projecting laterally from the casing, a coöperating fixed spirally-disposed incline located in the path of movement of the incline on the casing when the brakes are applied, a stop fixed upon said shaft adjacent to said casing 95 for relieving the longitudinal strain imposed upon said casing during the rotation thereof by the coöperating inclines.

In testimony whereof I sign this specification in the presence of two witnesses.

PHILLIP HIEN.
